COAL STOVE.

JAMES S. MARSH, OF LEWISBURGH, PENNSYLVANIA.

Letters Patent No. 59,775, dated November 20, 1866.

SPECIFICATION.

TO ALL WHOM IT MAY CONCERN:

Be it known that I, JAMES S. MARSH, of Lewisburgh, in the county of Union, and State of Pennsylvania, have invented a new and improved Stove; and I do hereby declare that the following is a full, clear, and exact description thereof, reference being had to the accompanying drawings, making a part of this specification, in which—

Figure 1 is an elevation of one side of the improved stove.

Figure 2 is a vertical central section through the stove and its pipes.

Figure 3 is a horizontal section through the stove, taken in the plane indicated by the dotted line *yy*.

Figure 4 is a section through the stove taken in the horizontal plane indicated by dotted line *xx*, fig. 2.

Figures 5, 6, 7, and 8, are views of a stove which is a modification of that shown in fig. 1.

Similar letters of reference indicate corresponding parts in the several figures.

This invention relates particularly to an improvement on that class of stoves which are chiefly constructed of sheet metal, and commonly termed drum stoves, but my invention is also applicable to many varieties of stoves for burning either wood or coal.

The nature of my invention consists in a stove which is constructed with an upper single wall for radiating heat into the room in which the stove is placed, a lower double wall enclosing an air space for the purpose of heating air, and one or more pipes leading from said air space through the smoke chamber, or through the smoke pipe of the stove, for the purpose of heating air and conducting heated air into upper apartments for warming purposes, as will be hereinafter described.

To enable others skilled in the art to understand my invention, I will describe its construction and operation.

The stove which I have represented in figs. 1, 2, 3, and 4, consists of a cylindrical body, A, which is secured at top and bottom to cap and base pieces B and C; the cylindrical portion, A, may be made of sheet iron, and the portions B, C, may be made of cast iron.

Within this stove is suitably arranged a cast-iron fire pot or lining, D, which is made with its upper end *a* flaring. The body or cylindrical portion of this fire pot is of much less diameter than the body, A, of the stove, so that a space, *b*, is formed between the cylinders A and D into which air is freely admitted through the perforations *cc*; the space *b* is closed at its top by the flange *a* of the lining D, and at its bottom by the base piece C, as shown in fig. 2. I thus construct a stove the lower portion of which is adapted for heating air to be conducted out of the room, while the upper portion is adapted for radiating heat directly into the room.

E is the opening through which fuel is supplied to the stove, F is the exit flue or stove pipe, and G is a heated-air pipe for conducting the heated air from the space *b*, surrounding the fire pot D, into an upper apartment. This pipe G, in figs. 1 and 2, conducts the heated air upward and through the smoke pipe F, where it receives additional heat from the escaping products of combustion, and from thence the pipe G may be carried off or upward to another apartment, where the heated air is allowed to escape.

Instead of leading a pipe from the chamber *b* outside of the stove, and thence through the smoke pipe as above described, several small pipes, *ggg*, may lead from this chamber *b*, through the flange *a*, of the inner wall D, into a drum, J, within the upper portion of the cylinder A, from which the heated air can be conducted by a pipe J', whithersoever it may be desired. In both instances which I have above mentioned it will be seen that the air which is heated in the chamber, *b*, will be re-heated by absorbing increments of heat from the escaping products of combustion. I thus absorb and utilize large quantities of heat which would be carried off up the chimney.

It will be seen that by forming an air-heating chamber around the fire pot or lining, D, having inlet openings near its bottom, and one or more outlet openings at or near its top, I obtain a free circulation of air through this chamber, which will have a tendency to cool and keep cool the fire-pot lining D, and to prevent it from rapid destruction by heat, particularly if this lining be made of cast iron.

Having thus described my invention, what I claim as new, and desire to secure by Letters Patent, is—

The construction of a stove with an upper, single, heat-radiating wall, and with a lower air-heating space, which is formed by the outer wall and fire pot, and which is provided with a pipe leading through the smoke pipe, or some other portion of the stove where it will be exposed to the escaping products of combustion as described.

JAMES S. MARSH.
